(57) **CLAIM**

The ornamental design for an interlocking toy, as shown and described.

DESCRIPTION

FIG. 1 is a perspective view of the interlocking toy in accordance with a first embodiment of the present invention;

FIG. 2 is a top view of the interlocking toy of FIG. 1, the bottom view being the same;

FIG. 3 is a first side view of the interlocking toy of FIG. 1, the second side view being the same;

FIG. 4 is a first end view of the interlocking toy of FIG. 1;

FIG. 5 is a second end view of the interlocking toy of FIG. 1;

FIG. 6 is a perspective view of the interlocking toy in accordance with a second embodiment of the present invention;

FIG. 7 is a top view of the interlocking toy of FIG. 6, the bottom view being the same;

FIG. 8 is a first side view of the interlocking toy of FIG. 6, the second side view being the same;

FIG. 9 is a first end view of the interlocking toy of FIG. 6; and,

FIG. 10 is a second end view of the interlocking toy of FIG. 6.
